APPARATUS FOR CONTROLLING HUMIDITY CONDITIONS IN AIR

Paul A. Herr, Neffsville, Pa.

Application October 21, 1953, Serial No. 387,343

2 Claims. (Cl. 261—91)

My invention relates broadly to apparatus for controlling humidity conditions in air and more particularly to apparatus for pumping out a portion of a heated main air stream, humidifying the said portion and returning the humidified portion to the main air stream for correspondingly conditioning the balance of the main air stream.

One of the objects of my invention is to provide an arrangement of a plenum humidifier readily installable in air ducts for extracting a portion of the heated air stream, humidifying the said portion and returning the humidified portion to the air stream for correspondingly humidifying the balance of the air stream.

Another object of my invention is to provide a construction of plenum humidifier which includes a motor-driven atomizer associated with a fluid reservoir attachable to one side of an air duct for pumping out a portion of the heated air from a main air stream, injecting an atomized moist mist into the extracted air stream and returning the conditioned portion of the air stream to the main air stream for correspondingly conditioning the balance of the air stream.

Still another object of my invention is to provide a construction of reservoir for fluid and a centrifugally operated atomizer associated therewith and which is readily attachable to the side wall of the plenum of a furnace for humidifying heated air delivered therefrom.

Still another object of my invention is to provide a construction of centrifugally operated motor-driven atomizer unit for a plenum humidifier having a minimum number of parts assembled in such an accessible manner that servicing and replacement of parts are practical.

Still another object of my invention is to provide a construction of plenum humidifier including a hot air intake attachable to a plenum through which a main air stream is force-flowed, a filter, a fluid reservoir, a centrifugal atomizer, and means for returning the atomized air to the main air stream for correspondingly humidifying the balance of the air being forced through the plenum.

Other and further objects of my invention reside in the construction, arrangement and mounting of a centrifugally operated atomizer for a plenum as set forth more fully in the specification hereinafter following by reference to the accompanying drawings, in which:

Figure 1 is a vertical sectional view through a plenum and the humidifier of my invention with certain of the parts shown in elevation and illustrating the manner of carrying out the humidifying method of my invention;

Fig. 2 is a horizontal sectional view taken substantially on line 2—2 of Fig. 1;

Fig. 3 is an enlarged vertical sectional view through the fluid atomizer of my invention with certain of the parts illustrated in elevation;

Fig. 4 is a bottom plan view of a portion of the centrifugal atomizing unit of my invention;

Fig. 5 is a top plan view of a portion of the atomizer unit of my invention;

Fig. 6 is a fragmentary cross-sectional view taken

2

through the lower portion of the atomizer unit on line 6—6 of Fig. 5;

Fig. 7 is a vertical cross-sectional view of the rotor of the atomizer unit;

Fig. 8 is a fragmentary top plan view of the rotor taken on line 8—8 of Fig. 7, and showing the motor-driven shaft in transverse section;

Fig. 9 is a transverse sectional view through the rotor taken substantially on line 9—9 of Fig. 7;

Fig. 10 is a vertical sectional view through the lower terminus of the rotor and illustrating particularly the construction of the fluid intake for the rotor; the insert for the end of the intake pipe being illustrated in the position ready to be assembled in the lower end of the intake pipe;

Fig. 11 is a fragmentary vertical sectional view showing the insert and the end of the intake pipe in assembled relation;

Fig. 12 is a perspective view of the insert for the end of the intake pipe, where the insert is cut away and illustrated in vertical section;

Fig. 13 is a horizontal sectional view through the intake pipe on line 13—13 of Fig. 7;

Fig. 14 is a horizontal sectional view through the hub of the rotor on line 14—14 of Fig. 7;

Fig. 15 is a horizontal sectional view taken through a portion of the atomizing screen associated with the rotor on line 15—15 of Fig. 16;

Fig. 16 is a fragmentary side elevational view of the atomizing screen;

Fig. 17 is a vertical sectional view taken on line 17—17 of Fig. 16;

Fig. 18 is a perspective view showing the manner of installing the plenum humidifier of my invention with relation to a furnace; and

Fig. 19 is a typical wiring and assembly diagram showing the manner in which the plenum humidifier of my invention is arranged to control the humidity of air force flowed through an air-conditioning system.

My invention is directed to apparatus for controlling humidity conditions in air where a humidifier may be readily installed in one side of an air distributing duct through which air is being force flowed. I provide a template having the dimensions of the intake and discharge apertures of the humidifier of my invention and

by mounting the template on the side wall of the plenum or air distributing duct, holes are drilled in the proper positions to allow attachment of the humidifier of my invention and to provide a guide for cutting out the central area for operation of the intake and discharge

functions of the humidifier. The humidifier comprises a fluid-containing reservoir, a filter interposed between the intake and humidifier which is attached to the plenum, an atomizer supported over the reservoir and a hood mounted over the atomizer.

The atomizer includes a centrifugal fan driven by an electric motor and which operates to extract a portion of the heated air flowing through the plenum, atomize the air with fluid from the reservoir and to return the atomized air to the air-flow stream in the plenum.

My invention includes a novel arrangement of parts in the atomizer assembled in a manner which renders the device readily accessible for servicing and repair.

Referring to the drawings in more detail, reference character 1 designates the furnace plenum leading from the furnace 2 shown more particularly in Figs. 18 and 19.

The rectangular aperture 3 cut in the side wall of the plenum by use of a template which marks the dimensional positions for cut-out apertures and the central opening in the plenum provides means for readily installing the humidifier of my invention in either old or new installations. The humidifier includes a reservoir portion represented at 4 which is attached to the plenum. 1

through flanges 5 and securing screws or bolts and nuts represented at 6. The reservoir includes a top portion 9 which is provided with a lateral reinforcement at 8 substantially coplanar with the side wall of the plenum and contiguous with the deflector 7 which projects into the air distributing duct 1 for gathering a portion of the force flow of air therethrough and directing the force flow of air into the reservoir. The top portion 9 of the reservoir includes a channelled peripheral edge 10 which engages the upstanding edge of the reservoir 4 around which the gasket 11 fits and serves as a seat for the shaped hood 12. The shaped hood 12 is provided with a sealing channel 14 at its lower edge which engages the sealing gasket 11 which envelopes the upstanding edge 10 of the reservoir. The hood 12 is attachable to the side wall of the plenum 1 by means of screws or bolts and nuts 13 extending through flanges 12a and fastened to the marginal edges of the opening 3 in the furnace plenum 1.

The top portion 9 has a central aperture 15 therein through which the atomizing unit 16 is mounted. The atomizing unit 16 is provided with a multiplicity of spaced block supports 17, 18, 19 and 20, each including resilient mounts 17a, 18a, 19a and 20a which are mounted adjacent ribs 17b, 18b, 19b and 20b disposed radially beneath the annular downturned rim 21 of the atomizing unit. The rim 21 is integrally molded as part of the depending cylindrical housing 22 of the atomizing unit, drain apertures 22a and 22b being provided in the base of the housing. The depending cylindrical housing 22 includes inwardly extending pedestals or ribs indicated more clearly in Fig. 5 at 23, 24, 25 and 26 molded internally with the housing 22 with the aid of recessed core apertures, indicated in Fig. 4 at 23a, 24a, 25a and 26a. The pedestals or ribs 23-26 serve as peripheral seats for the motor mounting plate 27 which contains radially extending lugs 27a, 27b, 27c and 27d, shown more clearly in Fig. 2, disposed in radial alignment with the pedestals or ribs 23, 24, 25 and 26 secured by means of bolts and or ribs 23b, 24b, 25b and 26b in a position peripherally spaced from the interior wall of the depending cylindrical housing 22. The bolts 23b-26b have their heads molded within the pedestals 23-26 and have their threaded ends extending upwardly through the lugs 27a-27d and engaged by removable cap screws. The motor mounting plate 27 has a central aperture 27f therein through which the hub 30 and shaft 31 of the driving motor 28 extends. The driving motor is secured to plate 27 by means of bolts 29. The motor mounting plate 27 is provided with a central seat 27e which insures a solid support for the motor. The outer portion of the motor mounting plate 27 terminates in a downwardly depending skirt 27g which forms a mounting means for the resilient skirt 55 on atomizer screen 54 which extends downwardly in the housing formed between motor mounting plate 27 and the bottom of the cylindrical housing 22.

The depending shaft 31 is provided with a key way 31a by means of which the rotor 32 is secured to shaft 31. The rotor 32 is molded from plastic and has a central bore 33 extending therethrough for receiving shaft 31, the bore 33 being formed in hub 34 which is disposed immediately below a frusto-conical portion or inclined face 35 of rotor 32 which connects with the flat circular disc 42 of the rotor. There are passages 36 formed in the hub 34 for the passage of narrow needle-like columns of water which are pumped from the reservoir 4 beneath the atomizer unit. Disc 42 is adjusted in its position on shaft 31 by set screw 37 which extends through hub 34 on an angle that is accessible from a position beneath the rotor for adjustment of disc 42 to enable the disc 42 to be centered within the housing formed between the bottom of cylindrical housing 22 and the motor mounting plate 27. Fluid is picked up from reservoir 4 by means of depending central tube 38 whose lower terminus is shown more clearly in Figs. 10-13 as including an intake

orifice 39 containing an intake aperture 40 associated with an inclined guide wall 41. When the terminus of the tube 38 containing the pickup intake orifice 39 is revolved at high speed by driving motor 28 the fluid is skimmed from the pool of fluid 46 and by centrifugal action of the inclined guide wall 41, the column of fluid is lifted through tube 38 and forced in columns through passages 36 where it is distributed by disc 42 for subsequent atomization. The disc 42 is provided with blades 43 on the lower surface thereof which operate as a centrifugal pump for extracting a portion of the air flowing through the furnace plenum 1. The blades 43 are arranged on disc 42 in such positions that they coat with the central aperture 44 in the bottom of the depending cylindrical housing 22 for drawing the air from plenum 1 through the filter shown at 63 and over the confining partition wall 45 of reservoir 4 and through the central aperture 44 for distribution through the atomizer screen 54, and through the annular passages 56 between the upper wall of the depending cylindrical housing 22 and the peripheral edge of the motor mounting plate 27 and in a path beneath hood 12 through aperture 3 where it is returned to the force flow of air in plenum 1. The air as it is force flowed in the plenum 1 through the central aperture 44 passes over the surface of the fluid 46 in reservoir 4, and picks up moisture therefrom.

The level of the fluid 46 in reservoir 4 is regulated by float valve 47 carried on angularly movable float valve arm 48 for controlling valve 49 connected to fluid supply 50, leading to pipe line 51 to shut-off valve 52. A suitable overflow 53 is provided in one side of the reservoir 4. A drain connection 57 is provided in the bottom of reservoir 4 connected to drain pipe 58 in which there may be a shut-off valve 59, as shown in Fig. 19. The power circuit shown at 60 may be connected in various ways through the humidistat 61 to the furnistat 62 from which circuit connections 28a extend to the driving motor 28. Thus the motor is energized whenever conditions call for increased moisture and the driving motor 28 is initiated in operation, pumping moist air through aperture 44 and pumping liquid through depending tube 38 from the fluid 46 in reservoir 4 where it is atomized by being sprayed in a thin film which moves up inclined wall 35 and is distributed in a thin film along the surface of flat disc 42 where it is spattered against the atomizer screen 54 in droplets which are broken down into a fine mist which is force flowed through passages 56 under the hood 12 and returned through aperture 3 to the plenum 1 where it mixes with the balance of the air being force flowed through plenum 1.

The air which is force flowed through plenum 1 is heated and is forced under pressure through the vertically extending duct indicated in Fig. 18. Only a portion of the heated air which is flowing at high velocity through the plenum 1 is skimmed off from the main body of the air flowing through plenum 1 for treatment by the humidifier of my invention. This portion of the air after humidification is returned to the main body of the air in plenum 1 at a location displaced from the position at which the air is treated from the plenum 1 in the direction of the flow of the air through plenum 1.

A filter 63 is interposed between the air intake to the humidifier and the air passage between the upper edge of the confining partition wall 45 and the aperture 44 leading to the atomizer unit. The filter 63 is constructed in the form of a slide which operates in a guide 64 which enables the filter to be readily removed and renewed from time to time.

The driving motor 28 may be connected in a variety of ways to the humidistat through the furnistat and the diagram shown in Fig. 19 is merely representative of one of several different arrangements and is to be considered in the illustrative sense and not in the limiting sense.

method of operation thereof highly efficient and practical, and while I have described my invention in certain embodiments I realize that modifications may be made and I desire that it be understood that no limitations upon my invention are intended other than may be imposed by the scope of the appended claims.

What I claim as new and desire to secure by Letters Patent of the United States, is as follows:

1. In a humidifying system, a vertically extending air distributing duct having an opening at one side thereof, a humidifier attached over the opening in the side of said air distributing duct and projecting horizontally therefrom and comprising a reservoir for fluid, an air intake disposed above said reservoir adjacent the opening in the lower portion of the side of said air distributing duct, a filter interposed between said air intake and one side of said reservoir immediately above the surface of the fluid therein, an atomizer unit, means for atomizing the fluid in said reservoir, means for mixing air extracted from said air distributing duct with the atomized fluid, a hood forming part of said humidifier for directing the mixed air and atomized fluid into the air distributing duct through the upper portion of the aforesaid opening in the side of said duct at a position above said air intake, said means for mixing air extracted from said air distributing duct with the atomized fluid being supported over said reservoir by a horizontal plate which divides said humidifier into two compartments and wherein in said last mentioned means includes a rotary pressure feed device having a central passage for air immediately above the surface of the fluid in said reservoir, the said plate extending beyond the limits of said reservoir and into said air distributing duct and forming a deflector for directing air into said air intake and guiding the humidified air from said hood into said air distributing duct.

2. In a humidifying system, a two-part casing, a vertically extending air distributing duct for confining the flow of an air stream and having an opening in the side

thereof, the two parts of said casing constituting upper and lower compartments, means for attaching each of the two parts of said casing in horizontal positions covering the opening in the side of said duct, said lower compartment including a fluid reservoir offset from the lower portion of the opening in said duct, an air filter disposed intermediate the said lower portion of said opening and said fluid reservoir, a horizontally extending plate engageable over the peripheral edge of said fluid reservoir and projecting into said duct and forming a means for skimming a portion of the air stream from said duct and diverting the air stream into said lower compartment, means supported by said plate for atomizing the fluid in said reservoir while allowing the forced flow of the diverted air stream into said upper compartment, the upper part of said casing comprising a hood detachably engaging at its horizontal edges the peripheral edge of said plate and said lower compartment, and detachably engaging along its vertical edges the marginal portions of said duct around the opening in the side thereof, said hood operating to direct the atomized air in a direction of flow reversed with respect to the direction of entry of the air into said lower compartment for returning the atomized air to the air stream within said duct in a position immediately adjacent the entry of the skimmed portion of the air stream into said lower compartment.
